UNITED STATES PATENT OFFICE.

GUST GUMMERSON, OF IRON MOUNTAIN, MICHIGAN.

ARTICLE-HOLDING DEVICE.

1,238,761.

Specification of Letters Patent.

Patented Sept. 4, 1917.

Application filed January 2, 1917. Serial No. 140,315.

To all whom it may concern:

Be it known that I, Gust Gummerson, a citizen of the United States, residing at Iron Mountain, in the county of Dickinson and 5 State of Michigan, have invented certain new and useful Improvements in Article-Holding Devices, of which the following is a specification.

This invention relates to package-holding devices, and has for its principal object to provide a simple and convenient means for supporting and gripping packages which may be left at designated points by mail carriers and others, and which are protected 10 from loss by being blown about by the wind or injured by rain falling upon said package.

A further object of the invention is to provide in such devices means whereby the 20 same may be operated quickly and without trouble by the person delivering the same so that no time will be lost in making his rounds for seeking means to secure the packages in positions at designated points.

25 A further object of the invention is to provide a device of the kind set forth with fixed and movable abutments, the latter being resiliently operated to serve as a gripping jaw, in connection with the fixed abutment to hold 30 a package therebetween and provided with an overhanging cover that will protect said package from the weather.

With the above as the principal objects in view the invention consists in the novel construction, combination, and arrangement of parts hereinafter described, pointed out in the appended claims, and illustrated in the accompanying drawings, in which—

40 Figure 1 is a vertical longitudinal section of the invention complete,

Fig. 2 is a top plan view of the same with the cover and abutments shown in section,

Fig. 3 is a transverse sectional view on the line 3—3 of Fig. 2.

45 In the drawings, 10 indicates a base-board or plate by means of which the device is secured to a post or fence, upon a house, door-step or other convenient place 11 which will afford secure protection and support for the 50 device. Fastened to one end of the base 10 and extending in a direction perpendicular thereto beyond one side is an upright abutment or plate 12, the upper end 13 of which is preferably bent over the base 10 for a 55 short distance.

Coöoperating with the abutment or plate

12 is a movable abutment 14 of substantially the same dimensions and in parallel relation with its upper edge 15 curved toward the similarly curved edge 13 of the fixed abutment. At the bottom of the abutment 14 are two guide rods 16 secured to the abutment and extending at right angles thereto through openings 17 in the fixed abutment, pins 18 being passed through the ends of 60 the rod 16 to prevent withdrawal from the openings 17. On the outer side of the movable abutment is a handle 19 by which the abutment may be moved toward and from the fixed abutment 12, while to secure easier 65 movement of this abutment there is mounted at the bottom at substantially the central line thereof a roller 20 turning in journals 21 and bearing in a shallow longitudinal slot 22 formed in the top of the base 10. 70

75 Normally the movable abutment is maintained in close relation to the fixed abutment by means of a spring 23 connected at one end to a lip 24 on the abutment 14 and at its other end to a bracket 25 that projects beyond the side of the base to which the fixed abutment 12 is attached. This spring passes freely through an opening 26 in the fixed abutment and will serve to grip any package placed between the two abutments with sufficient firmness to prevent falling to the ground or being blown out of position by the wind. As a further guide for the movable abutment 14 there is provided a rail 27 secured to the base plate on 80 each side thereof, and lying parallel to each other and to the line of movement of the abutment 14.

85 These rails also serve as a support for the article or articles between the abutments. 90

As protection against rain and snow a cover plate 28 extends over the device sufficiently high to enable all packages of average size to be placed thereunder, said cover plate extending from a point near the 100 rear end of the base to which it is connected by uprights 29 and then extends forward beyond the fixed abutment where, twining downwardly at an angle, it is bent around the bracket 25 and again back toward the 105 base in a horizontal direction to which it is fixed in any appropriate manner.

110 As thus described, the invention is shown to be a simple and convenient device which in use is attached by screws 30 to any fixed support, and when a mail carrier or other person desires to leave a package for a per-

son in the device, he has merely to grasp the handle 19 in one hand, draw the abutment 14 backwardly and with the other hand insert the package between the two abutments; then loosening the handle 19, the abutment 14 closes upon the package and grips the same therebetween and between the abutment 12. A device of this kind will be very useful on rural mail routes where a postman often finds difficulty in securing a package in a fixed position. This device may also be secured to houses and made in proper sizes to be placed on a desk for holding files and other papers.

15. What I claim is:

1. In a device of the kind described, the combination with a base adapted to be secured in position, a fixed abutment at one end of said base and projecting perpendicularly thereto at one side, a movable abutment adapted to coöperate with the fixed abutment for holding articles therebetween, resilient means for normally maintaining the movable abutment in contact with the fixed abutment, guide bars on the movable abutment passing through openings in the fixed abutment, and a fixed rail on the base at each side of the movable abutment to guide said abutment and also to support the articles held between said abutments.
20. In a device of the class described, the combination with a base adapted to be se-
- 25
- 30

cured in position, an abutment fixed at one end of said base and extending perpendicularly thereto, a bracket projecting outwardly 35 from said end of the base, a movable abutment coöperating with said fixed abutment for holding packages therebetween, a spring attached to said movable abutment and to said bracket for normally holding the latter 40 abutment against the fixed abutment and for gripping contained articles, guide bars secured to the movable abutment and slideable through openings in the fixed abutment, a fixed guide plate secured to the 45 base on each side of the movable abutment and extending from the fixed abutment to the limit of movement of the movable abutment, a roller mounted on the movable abutment and traveling in a groove in the base 50 for supporting the movable abutment above said base, means on the latter abutment for withdrawing it from the fixed abutment, and a broad cover plate secured at one end to an end of said base and extending thence 55 forwardly, upwardly and rearwardly to form a cover for the contained article.

In testimony whereof I affix my signature in presence of two witnesses.

GUST GUMMERSON.
